UNITED STATES PATENT OFFICE.

CHARLES ANDREWS, JR., OF ROCKFORD, ILLINOIS, ASSIGNOR TO ANDREWS
WIRE & IRON WORKS, OF SAME PLACE.

CALF-WEANER.

SPECIFICATION forming part of Letters Patent No. 683,873, dated October 1, 1901.

Application filed August 27, 1900. Serial No. 28,239. (No model.)

To all whom it may concern:

Be it known that I, CHARLES ANDREWS, Jr., a citizen of the United States, residing at Rockford, in the county of Winnebago and State of Illinois, have invented certain new and useful Improvements in Calf-Weaners, of which the following is a specification.

The object of this invention is to construct a calf-weaner in which a combined head and chin band is formed of a single piece of wire and to which is rigidly attached a nose-loop and means for securing the weaner to the head of the calf.

In the accompanying drawings, Figure 1 is a side elevation of my improved calf-weaner. Fig. 2 is a view of the weaner as seen from the head end.

The weaner is preferably composed of a combined head and chin band of substantially oval shape and formed from a single piece of wire, the upper portion 1 being the head-band and the lower portion 2 being the chin-band. A U-shaped nose-loop 3 is connected at its ends to the parallel portions of the combined head and chin band and is the dividing-line separating the band into its head and chin sections. A brace 4 connects directly with the outer end of the nose-loop and the upper portion of the head-band. A wire-netting 5 covers that portion of the weaner between the head-band and nose-loop. To the combined head and chin band are pivotally connected two ears, each ear composed of an arm 6 at its upper portion loosely encircling the head-band and an elongated loop portion 7 at its lower end encircling the chin-band, the construction of said ears being such that a sort of pivotal mounting is obtained, whereby the vertical wires of the combined head

and chin band may play freely back and forth to a considerable extent in said elongated loop portions 7, thus permitting the front part of the weaner to rise and fall, according to the position of the head of the calf. Straps 8 are connected to the ears, by means of which the weaner is attached to the head of the calf. By means of the ears pivoted to the main frame and the loops guided in connection with the main frame the main frame can rise and fall, which permits the calf to eat from the ground, but prevents it from sucking.

I claim as my invention—

1. The combination with a calf-weaner, of two ears pivotally connected thereto, each of said ears being provided at its lower end with an elongated opening loosely embracing the weaner whereby the front portion of the latter may have a rising-and-falling movement independent of the ears, and means attached to the ears and adapted to pass over the head of a calf for securing the weaner in position.

2. A calf-weaner comprising a rigid frame composed of a combined head and chin band, and nose-loop, and a wire - netting covering that portion of the weaner between the head-band and nose-loop, and two ears pivotally connected to the weaner, each ear being provided at its lower end with an elongated loop portion loosely engaging the vertical wires of the combined head and chin band whereby the front portion of the weaner is permitted to rise and fall for the purpose specified.

CHARLES ANDREWS, JR.
